UNITED STATES PATENT OFFICE.

EDWARD C. WOOD, OF SOMERVILLE, MASSACHUSETTS, ASSIGNOR TO SUBMARINE SIGNAL COMPANY, OF WATERVILLE, MAINE, A CORPORATION OF MAINE.

ELECTRICALLY-OPERATED BELL FOR SUBMARINE SIGNALING.

1,186,961.

Specification of Letters Patent. Patented June 13, 1916.

Application filed February 12, 1912. Serial No. 677,264.

To all whom it may concern:

Be it known that I, EDWARD C. WOOD, of Somerville, in the county of Middlesex and State of Massachusetts, a citizen of the 5 United States, have invented a new and useful Improvement in Electrically-Operated Bells for Submarine Signaling, of which the following is a specification.

Means for operating a submarine bell by 10 electricity have been already devised and tried with more or less success, but in the apparatus heretofore constructed electrical means have been applied either directly to the clapper to throw it or else to the 15 bell itself for the purpose of attracting and repelling the walls of the bell so as to set up vibrations in them. In the present case electrical means are applied for the purpose of storing energy and hence securing 20 a blow from the clapper upon the bell which blow shall always be of substantially the same force so that the vibrations or 25 sound waves from the bell will always reach a substantially given distance. Moreover, the construction herein shown is especially 30 useful for signaling from submarine boats, for which purpose, while the bell itself is in contact with the water, the mechanism may be located within the boat or upon its deck in a watertight compartment.

This invention will be understood by reference to the drawings in which its preferred form is shown.

Figure 1 is a longitudinal section of the 35 casing on which the bell is mounted and which contains the mechanism for operating the bell, the section being taken on line 1—1 of Fig. 2. Fig. 2 is a view showing the casing spring, bell and portion of 40 the clapper arm in section, the other parts being in elevation. Fig. 3 is a section on line 3—3 of Fig. 2, showing the cam and the means operated by it. Fig. 4 is a section of the cam, showing the clutch mechanism, and Fig. 5 is a section on line 5—5 of Fig. 1.

A is a box or casing suitably strengthened by ribs or otherwise and serving as a protection to the mechanism. It is provided 50 with a cover A¹ which is bolted to the casing A in such a manner as to form an airtight inclosure therein. For this purpose

a gasket a may be conveniently used, fitting into a suitable groove in the cover.

Upon the cover A¹ is mounted a boss A² 55 having an opening through it as at A³ for the clapper arm and upon this boss is mounted the bell B. A suitable washer B¹ and rubberneck B², both of well known description, are provided to form with clapper arm B³ a watertight joint to prevent the leakage of water from without into the chamber within the casing A. The bell B is bolted to the boss by bolts b and the casing itself is bolted by bolts b¹ to the deck 60 A⁴ of the vessel, or it may be supported in any other way as seems best.

The clapper is mounted on the end of the clapper arm B³ which is hung on a pin b², which serves as its fulcrum and which is 70 supported in suitable journals formed in hangers b⁴ bolted to the under side of the cover A¹.

b⁵ is a clamp by means of which the rubberneck is held about the clapper to form 75 an airtight joint therewith.

The clapper arm B³ is a lever having an arm C forming a continuation of the clapper arm B³ and a pair of arms D at right angles thereto, one on each side of the arm 80 C and forming bell-cranks. The arms D are pivotally connected to a rod D¹ having an enlargement d at its upper end and being spread slightly at its lower end. Its lower end d¹ carries a nut d² to form a 85 guide within the block D², which is secured to the bottom or flooring E of the frame upon which the mechanism is supported. On top of the block D² is mounted a ring D³ carrying perforated webs, the 90 perforations being arranged to receive the lower end of a spring D⁴ which screws into them. The enlargement d at the upper end of the rod is in like manner provided with webs and perforations into which the upper end of the spring may be screwed so that the spring is firmly held at each end and operates as an expansion spring. 95

d⁵ is a plug of rubber or other elastic material which sets into a screw cap d⁶ and 100 forms the bottom of the cavity in the block D². This cap or plug d⁶ is screwed into an opening in the floor E so as to be adjustable therein and hence adjust the stroke of

the rod D¹. The spring D⁴ is expanded by the movement of the straight arm C which forms a continuation of the clapper arm and which acts through the crank arms D. 5 By throwing the arm C to the left (see Fig. 2) the arm D raises the rod D¹ and elongates the spring D⁴, and when the power acting on the arm C is released the contraction of the spring D⁴ throws the clapper per arm B³ over and causes the clapper to strike the bell. The cushion d³ when struck by the bottom of the rod causes a slight rebound on the part of the clapper, its position having been adjusted so that it will 10 normally so hold the rod D¹ that the clapper will be out of contact with the bell.

The mechanism for moving the lower end or arm C of the clapper arm B³ so that it will elongate the spring D⁴ is as follows:—

10 F is an electric motor. The current is supplied to this motor through the wires f which are connected to suitable binding screws f¹, each binding screw being in contact with a spring-contact f² connected with other binding screws f³, each carrying wires f⁴ running through the plug L² to a source of current outside the casing. The motor F is a constantly-running motor and carries on its shaft a pinion F¹ engaging a gear F² 15 on a shaft F³ suitably mounted in ball bearings carried by supports E¹ mounted on the flooring E. On this shaft F³ is also mounted a pinion F⁴ which engages a gear F⁵ on a shaft F⁶ supported in hangers A⁵ bolted to 20 the cover A¹. The shaft F⁶ has an enlargement or drum G forming one member of a clutch by means of which a cam H is operated. The cam H is mounted with ball bearings on the shaft F⁶ and is free to turn 25 0 thereon. The drum G has wound tightly upon it a spring g one end g¹ of which sets into an opening or socket h in the inner periphery of the cam, while the other end g² projects at right angles through the 30 head or end wall of the cam as at h¹ (see Fig. 4). J is a yoke-piece pivotally mounted as at j on a support J¹ mounted on the flooring E and having a toe j¹ by which its movement in one direction is limited, that 35 0 movement being caused by a spring j² which lies between the yoke-piece J and an upright J² forming part of the support J¹. This yoke-piece J as shown forms an armature for an electro-magnet K which is supported 40 5 from an upright K¹ also mounted on the flooring E. Current is brought to this electro-magnet from some suitable source outside the casing A by the wires k through the plug L¹. When current is applied to the 45 0 electro-magnet the yoke-piece J will be attracted, and when the circuit is broken the yoke-piece will be released and by virtue of the spring j² the yoke-piece will be thrown to the right (see Fig. 2) until the toe j¹ 50 5 comes in contact with the part J¹ below it.

In Fig. 2 the yoke-piece is shown in its attracted position. This yoke-piece is an escapement controlled by the electro-magnet K and its action is such as to control the operation of the spring clutch. The direction of rotation of the drum is shown in Fig. 2 by the arrow, and from Fig. 4 it will be seen that if the end g² of the spring g is restrained the grip of the spring on the drum will be released and the drum will rotate without carrying the spring and cam with it. The spring, however, normally is wound sufficiently tightly on the drum G to grip it so that the drum will carry the cam H with it as it rotates because of the connection between the other end of the spring g¹ and the cam. In Fig. 2 it will be noted that the upper end of one of the escapement arms J has a finger or overhang j⁵ which is there shown as engaging the end g² of the spring. It will be seen therefore that while the drum G is constantly being moved by means of the motor F in the direction of the arrow, the spring being held in a loose position with relation to the drum, the drum rotates without any action upon the cam. The breaking of the circuit through the electro-magnet K, however, will release the end of the spring g²; that is, will allow the yoke-piece to move to the right (see Fig. 2) so that the spring being released will grip the drum G and carry the cam around with it. But in the meantime, the other arm j⁶ of the escapement has been moved into the path of the end g² of the spring so that when the drum G has turned about 180° the end g² of the spring will engage the end j⁶ of the yoke-piece J and rest on it and the spring will again be spread so as to release the drum from the cam and this condition will remain until the yoke-piece is again attracted by the electro-magnet. The cam is in the form of a hollow cylinder having bearings which rest upon the shaft F⁶ carrying the drum G and in which the shaft F⁶ is free to turn. For approximately 180° it has a plain cylindrical surface of considerable width, the cam surface proper h² starting at a point substantially 180° from the opening h¹ through which the end g² of the spring passes. From that point it rises gradually to a point alongside of the opening h¹ where it reaches its extreme height and from which it drops abruptly. In connection with this cam surface there is a cam roll H¹ mounted on the end of the extension C of the clapper arm B³ and the purpose of this roll is to gradually ride up the cam surface, pushing the clapper to the right (see Fig. 2) and gradually elongating the spring D⁴. In order to prevent undue wear to the cam roll which might result from the constant dropping over the end of the cam surface, it is best to provide the arm C with feet H² one on each side of the roll H¹, these feet being 100 105 110 115 120 125 130

both alike and at their extremity projecting somewhat beyond the periphery of the cam roll H^1 . These feet H^2 are separated by the roll H^1 and are sufficiently far apart to 5 straddle the cam surface h^2 . On each side of the cam surface h^2 are auxiliary surfaces h^3 which, during all but a few degrees of the circumference of the cam, are cylindrical, but from a point approaching the highest 10 extremity of the cam surface h^2 develop auxiliary cam surfaces h^4 of a height corresponding to the height of the cam surface h^2 itself, and these surfaces are so located that as the cam rotates while the clapper is 15 gradually thrown to the right (see Fig. 2) by the engagement of the cam roll H^1 with the cam surface h^2 just before the cam roll is to fall off from the cam surface h^2 , that is, just before the cam surface h^2 resumes its cylindrical 20 form, the arms H^2 begin to bear upon their cam surfaces h^4 and take the brunt not only of the final lifting or moving of the clapper, but also take the entire force of the throw of the clapper caused by the spring D^4 25 when it resumes its normal position. Thus the roll acts rather more as a friction roll than as a cam roll, for although bearing upon the cam surface h^2 , it gradually moves the clapper against the force of the spring D^4 30 into striking position. The brunt of the impact of the arm C on the cylindrical portion of the cam, when the cam surface has been moved by it, is taken by the arms H^2 and not by the roll H^1 . This may not be essential in 35 all cases, but it is very desirable as the arms may be made of any desired strength and consequently will save considerable wear of the roll and its bearings.

The floor E is preferably supported by 40 suitable hangers E^1 from the under side of the cover A^1 . This enables the apparatus to be put together and hung from the cover A^1 and the whole to be put in place when the cover is set into place. The contact 45 springs f^2 simplify the setting of the mechanism into the case. Similar contact springs may be utilized to connect the device with the source of current for the electro-magnet K .

50 The casing is provided with two openings: one into which the pipe L leads and which may be connected with a suitable air compressor for the purpose of maintaining a heavier pressure in the casing than that 55 of the water outside of the casing so as to maintain the parts watertight in case there is any tendency to leak where the cover is attached to the casing, and the other carrying a plug L^1 (see Fig. 5) having a packing L^2 of rubber or the like with openings 60 l through it through which to lead the electrical conductors. By making this packing of soft rubber and providing it with a metal washer l^1 on each side, the whole being of sufficient length to extend beyond the plug 65

L^1 , and screwing a nut tightly onto the plug L^1 the packing L^2 will be so squeezed as to form an airtight joint with each wire f^4 , k . This is only shown diagrammatically in Fig. 2.

The operation of this bell is as follows: Sufficient current is applied to the motor F to cause it to perform the necessary mechanical operation of the turning of the drum G . Current is also supplied to the 70 electro-magnet K , there being in the circuit a suitable key by which the circuit may be made and broken at appropriate times. Suppose the parts to be in the position shown in Fig. 2 which is an intermediate 75 position, the circuit through the electro-magnet is broken, thereby releasing the toe-piece j^5 from contact with the end g^2 of the spring g . The spring grabs the drum G so that it is rotated by the drum, its rotation 80 carrying with it the cam H until the spring end g^2 engages the end j^6 of the escapement arm. This is the normal position of the parts when they are at rest. To cause the 85 clapper to strike the bell, the circuit through the electro-magnet is again closed thus attracting the yoke-piece J and withdrawing the arm j^8 from under the spring end g^2 so that the spring grabs the drum G , and the cam is carried about 180° to the position 90 shown in Fig. 2 when the finger j^6 catches the end g^2 of the spring and releases the drum. The circuit is again broken and the 95 spring released so that the cam again rotates about 180° and until the spring end g^2 again rests upon the arm j^8 . The circuit through K is again closed and opened at the 100 key to cause the next operation of the clapper. The first action of the cam surface is to throw the extension of the clapper arm 105 to the left and the clapper to the right (see Fig. 2), the roll H^1 riding up on the cam surface until the feet H^2 engage their portion of the cam surface and then the parts are held by the contact g , g^2 and j^8 until 110 the circuit through K is closed. On the closing of the circuit at the key the escapement is attracted by the electromagnet so that the arm j^6 is pulled from under the end g^2 of the spring and the clutch spring 115 grabs the drum G and the cam is carried around until the projection j^5 engages the spring end g^2 . During this movement of the cam the feet H^2 and the roll H^1 fall off 120 from the cam surface onto the cylindrical portion of the cam, thus releasing the spring D^4 which having been elongated on its release pulls the clapper over to the left (see Fig. 2) causing it to strike the bell and the elastic cushion d^2 causing a slight reaction 125 of the rod D^1 so that the clapper does not remain in contact with the bell. Upon the breaking of the circuit again the spring end is released by the projection j^5 and the 130 spring again grabs the drum G and the cam

turns until the spring end again rides on the end j^6 of the yoke arm, thus completing the cycle of movement until the circuit is again closed. The closing of the circuit thus 5 releases the cam for about half a revolution, stops it and upon the opening of the circuit again it again is released for about half a revolution until the spring end g^2 brings up upon the yoke arm j^6 where it is held until 10 such time as it is desired to cause another blow to be struck upon the bell when the circuit is closed again. In this way the clapper-operating mechanism is so controlled that only one stroke of the bell can 15 be given for each closing of the circuit and hence the signals are under absolute control. Such a control is especially useful and necessary when the signals are to be originated in a submarine boat and are to be 20 used as a means of conveying messages from one boat to a station on shore or on another boat.

The circuit breaker may be any usual 25 form of telegraph key located with the source of electricity for the electromagnet in any part of the submarine or other vessel and the bell may be sounded at will and according to any desired code.

It is not meant to limit the invention in 30 its details to the specific construction shown for there may be other forms of clutch and other cam motions equally useful to those shown, the essential feature of the invention being a constantly-running motor, preferably electrical and means for causing it to be operable at will upon the clapper or other signaling means. Nor is it meant to limit the invention to the form of power 35 accumulator shown as other forms may be used and under certain circumstances where the clapper is lifted by the cam or its equivalent its weight would answer on falling to strike blows of equal force.

In using the term "operable by hand" I 40 do not mean that the device by which the throwing in of the clutch is caused shall necessarily be hand-operated, but that it shall be of a character either electrical or otherwise which requires a definite act either 45 manual or otherwise, by which one member of the clutch is caused to engage the other member, the final disengagement of the clutch members being automatic so that when put into engagement its period of 50 operation is necessarily limited by the action of the automatic throw-off. Thus the period during which the clapper is operated will necessarily be limited because of the automatic disengagement to which I have referred 55 and my construction as described above prevents any new engagement of the clutch until after the automatic disengagement has taken place.

What I claim as my invention is:—

60 1. In a device of the kind described, a

sounder, a clapper, a continuously-operating motor, and means for connecting said motor and said clapper comprising a clutch and electrical means operable at will adapted to effect the engagement of said clutch and cause its disengagement after a predetermined movement thereof whereby said sounder will be caused to give a predetermined signal, said electrical means comprising an electro-magnet controllable from 70 a distance and means operable by said electro-magnet and located between said electro-magnet and said clutch adapted to engage said clutch both at the moment when said electro-magnet is energized and also when 75 it is released.

2. In a device of the character specified, a sounder, a constantly-running motor, a clutch connected to said motor, a cam connected to said clutch and connectible thereby to said motor and means whereby said clutch may be operated at will to cause the said cam to take a plurality of steps in making a complete revolution and will then be disconnected from said motor, and means 85 located between said cam and said sounder whereby the complete revolution of said cam will cause a single operation of said sounder.

3. In a device of the character specified, a sounder, a constantly-running motor, a clutch connected to said motor, a cam connected to said clutch and connectible thereby to said motor and means whereby said clutch may be operated to cause the said cam to take a plurality of steps in making a complete revolution, said means comprising an escapement lever adapted to engage said clutch and means for operating it, and means located between said cam and said sounder whereby the complete rotation of 100 said cam will cause a single operation of 105 said sounder.

4. A device of the kind described comprising a sounder, a clapper and a power accumulator to operate said clapper and means for storing power in said power accumulator comprising a constantly-running electric motor and means adapted to connect said motor with said power accumulator at will comprising a clutch, a cam, 110 means for operating said clutch electrically to connect said cam and said motor, whereby said cam will be given a limited movement, and means connected to said power accumulator adapted to engage said cam whereby 115 said cam will cause said power accumulator to accumulate power and to release said power when accumulated and operate said clapper.

5. A device of the kind described comprising a sounder, a clapper and a power accumulator to operate said clapper and means for storing power in said power accumulator comprising a constantly-running electric motor and means adapted to 120 125 130

connect said motor with said power accumulator at will comprising a cam, a clutch adapted to connect said cam and said motor, an escapement adapted to engage said clutch, 5 an electro-magnet and means for energizing it at will, said escapement being located and adapted to be operated by the electro-magnet.

6. In a device of the character specified, 0 a sounder, a constantly-running motor, a clutch connected to said motor, a cam connected to said clutch and connectible thereby to said motor and means whereby said clutch may be operated to cause the said cam to take a plurality of steps in making a complete revolution, said means comprising an escapement lever adapted to engage said clutch and an electro-magnet adapted when energized to attract said escapement lever, 5 and means located between said cam and said sounder whereby the complete rotation of said cam will cause a single operation of said sounder.

7. A device of the kind described comprising in combination a sounder and a clapper, 5 a constantly-rotating motor, a clutch adapted to be connected thereto, a cam connected to said clutch to be operated by said motor, means whereby said clapper may be operated 10 by said cam, and means for operating said clutch intermittently to connect said cam and said motor comprising an electro-magnet, an armature mounted to be attracted thereby and carrying an escapement yoke one arm of 15 which is adapted to engage one element of said clutch when said electro-magnet is electrically excited and the other arm of which is adapted to engage said element when said electro-magnet is dead and means 20 for electrically exciting said electro-magnet at will.

8. In a device of the character specified, 0 a sounder, a constantly-running motor, a clutch connected to said motor, a cam connected to said clutch and connectible thereby to said motor and means whereby said clutch may be operated to cause the said cam to take a plurality of steps in making a complete revolution, said clutch having a projecting arm whereby it may be connected to and disconnected from said motor, in combination with an escapement 15

lever having two arms each adapted to engage and restrain the movement of said clutch arm, means for rocking said escapement lever comprising an electro-magnet and means located between said cam and said sounder whereby a complete rotation of said cam will cause a single operation of 55 said sounder. 60

9. A device of the kind described comprising a sounder and a clapper, a cam and means for operating said cam, said cam having a gradually swelling surface and an abruptly swelling surface, said swelling 65 surfaces terminating abruptly on a line parallel with the axis of the cam roller, and said clapper having a forked arm and a roller located between said forks, said roller being located to run on the gradually swelling 70 cam surface and said forks to engage said abruptly swelling cam surface, in combination with means for throwing said clapper upon the release of said arm by said cam, the forks on said arm projecting slightly in 75 advance of said roller whereby said forks will lift said roller off the cam surface upon reaching the abruptly swelling surface of the cam and in falling off from the swell will take the impact of the blow against the 80 normal surface of the cam.

10. In a device of the kind described, a sounder, a clapper and means to operate said clapper comprising a constantly-moving motor and a clutch adapted to connect said 85 motor and said clapper and cause a single operation of said clapper and means operating thereafter to engage said clutch and cause it to disengage said motor and clapper.

11. In a device of the kind described, a sounder, a clapper and means to operate said clapper to cause it to give a single blow to said sounder comprising a constantly-running motor, and a clutch operable by hand to connect said clapper and said motor 95 and means adapted to engage said clutch at a predetermined point in its revolution and separate its members, whereby the period of said connection shall be automatically determined.
